UNITED STATES PATENT OFFICE.

AUGUSTIN W. MCINTYRE, OF CHICAGO, ILLINOIS, ASSIGNOR, BY MESNE ASSIGNMENTS, TO THE AMERICAN CAR-WHEEL GRINDING COMPANY, OF SAME PLACE.

GRINDING-MACHINE.

SPECIFICATION forming part of Letters Patent No. 288,718, dated November 20, 1883.

Application filed December 8, 1882. Renewed September 24, 1883. (No model.)

To all whom it may concern:

Be it known that I, AUGUSTIN W. MCINTYRE, a citizen of the United States, residing at Chicago, in the county of Cook and State of Illinois, have invented certain new and useful Improvements in Grinding-Machines, of which the following is a full, clear, and exact description, sufficient to enable any one skilled in the art to which my invention appertains to manufacture and use the same.

Although, for the sake of brevity, I have thus entitled my invention "improvements in grinding-machines," and in the annexed drawings have illustrated the same as applied to the grinding of railway-car wheels, I wish it distinctly understood that such improvements are applicable as well to the cutting, abrading, or polishing of all cylindrical, conical, or conoidal bodies of metal, wood, stone, or the like.

My present invention has for its objects, first, to furnish improved mechanism whereby the work can be accurately positioned and securely sustained during the grinding operation; second, to provide means for imparting a uniform, smooth revolution to the object to be ground; third, to improve the mechanism for sustaining and operating the grinding or cutting wheels; fourth, to furnish mechanism for automatically compensating for the wearing away of the grinding-wheels, and thus keeping the same constantly up to their work; fifth, to provide the grinding or cutting wheels with hoods and exhaust apparatus, whereby the dust from the work and the wheels may be collected and withdrawn, and the liability of accident from the bursting of carelessly-placed wheels shall be avoided; and, sixth, to improve the construction of the grinding-wheels and the means for centering and securing the same on their mandrels. These several objects of invention I have accomplished by the mechanism hereinafter described, illustrated in the accompanying drawings, and particularly defined in the claims at the end of this specification.

Figure I is a plan view, with parts removed, of a machine especially suited for the grinding of car-wheels, and adapted to operate with

four pairs or sets of abrading-wheels. Fig. II is a view, in vertical section on line *a b* of Fig. III, of the axle-bearing, its housing, and means for adjusting the same. Fig. III is a view in vertical section on line *c d* of Fig. II. Fig. IV is a detail outer side view of one of the housings of the work-holding standards. Fig. V is a view in vertical section, similar to Fig. II, but showing the bearings in position to receive the axle of the car-wheels. Fig. VI is a view in inner side elevation of one-half of the machine. Fig. VII is a side view, partly in section, of the screw-jack and friction-gear of the mechanism for revolving the work. Fig. VIII is a plan view of the friction-gear detached. Fig. IX is a view partly in side elevation and partly in section on line *e f* of Fig. X. Fig. X is a view in vertical transverse section on line *g h* of Fig. IX. Fig. X^a is a view, partly in vertical section, of the conical friction-clutch. Fig. XI is a view in side elevation of a standard and wheels for sustaining one pair of grinding-wheels, one wheel being removed and the hood of the other being shown in vertical section. Fig. XII is a view in front elevation of a standard and mechanism for sustaining one pair of grinding-wheels. Fig. XIII is a detail plan view of the cam-gear or pattern apparatus of a shape especially adapted for grinding car-wheels. Fig. XIV is a view in vertical section on line *i k* of Fig. XIII, showing also adjacent parts. Fig. XV is a view in vertical section on line *l m* of Fig. XIV. Fig. XVI is a detail view, partly in plan and partly in horizontal section, of the mechanism for compensating for the wear of the grinding-wheels. Fig. XVII is a view in section on line *n o* of Fig. XVI. Fig. XVII^a is a view in vertical section on line *p q* of Fig. XVII. Fig. XVIII is a view in section on line *r s* of Fig. XVI. Fig. XVIII^a is a detail. Fig. XIX is a detail view, in vertical longitudinal section, of an emery grinding-wheel, showing the manner of attaching the same. Fig. XX is an inner side view of a portion of the emery-wheel. Figs. XXI and XXII are respectively views in vertical longitudinal and vertical transverse section of a modified construction of bearing for the mandrel of the grinding-wheels.

Fig. XXIII is a detail view of a modified form of pattern device and adjacent parts. Fig. XXIV is a detail plan view of such modified form of pattern device. Fig. XXV is a detail view, in vertical transverse section, of the articulated joint of the exhaust-pipe. Fig. XXVI is a detail view, partly in plan and partly in horizontal transverse section, of a portion of the exhaust apparatus. Fig. XXVII is a detail view, in side elevation, of a portion of the exhaust apparatus. Fig. XXVIII is a detail view, in section on line *t u* of Fig. XXIX, of a cut-off which may be applied to limit automatically the travel of the main carriage. Fig. XXIX is a view in section on line *v w* of Fig. XXVIII, showing the main spindle and portions of the cut-off in perspective. Fig. XXX is a plan view of one of the jaws of the cut-off. Fig. XXXI is a view in side elevation of the cut-off mechanism to limit the travel of the main table.

Like numbers and letters of reference indicate corresponding parts in the various views of the drawings.

25 A designates the bed-plate or base of the machine, to which, intermediate the four sets of grinding-wheels, are secured the work-holding standards *A'* by means of the set-bolts 1, which enter the T-shaped channels 1^a in the base. By this construction the standards—one or both—can be readily adjusted to accommodate cylindrical bodies of different lengths. The standards *A'*, which are hollow castings, are each provided at the top with the extension 2, the side ledges, 3, and the central slot, 4, and upon the top of these standards rest the housings *A*², which have the flanges 5, adapted to embrace the ledges 3, and thus retain the housings securely upon their seats. The bottom of each of the outer flanges, 5, is formed of a separable strip attached by means of screws, and between these flanges and the corresponding ledges are placed the friction key-strips 5^b, which are rendered adjustable by 45 means of set-screws, and serve to compensate for any wear of parts and retain the housings firmly upon the standards. From the base of each housing depends a cylindrical extension, 6, which passes through the slot 4 of the standard, and bears a threaded lug, 7, through which extends the spindle *A*³, journaled at its ends in the top of the standard. The spindles *A*³ are furnished, as shown, with suitable wrench-bars, by turning which the housings 55 can be moved upon the standards, and cylinders of different diameters can thus be readily presented to the action of the cutting or abrading tools upon one side of the machine. In the cylindrical extensions of the housings 60 are fitted the threaded sleeves 8, through which pass the spindles 9, to the top of which are keyed the bottom bearing-blocks, 10, upon which rest the ends of the axle of the cylinder to be ground. The tops of the housings 65 are cut out, as shown, and within the spaces thus formed rest the side bearing-blocks, 11, which are adjusted by means of the set-

screws 12 and guided by the flanges 13. Each of the housings is provided upon its outer side with a trough-shaped head or extension, 14, 70 containing the mechanism for centering the cylinders preparatory to the adjustment of the bearing-blocks or bearings. The enlarged end 15 of the head 14 is perforated to receive the plain cut-away end of the short screw-block 75 16, securely held therein. Over the threaded portion of each screw-block 16 fits an interiorly-threaded screw-nut, 17, provided upon its face with the loose annular friction-plate 18, adapted to bear against the end of the axle 80 and prevent its longitudinal displacement. This screw-block 16 is furnished with a central perforation having screw-threads in reverse of those on its exterior, and in this perforation fits a correspondingly-threaded pointed center-pin, 19, which passes through a perforation in the screw-nut 17, and which is provided with the spline or key 20, adapted to fit a corresponding groove in the screw-nut, so that the two shall turn together. On the outside of the base-standards *A'*, below the flanges 90 5, may be fitted a scale or division, if desired, to enable the more accurate and ready adjustment of the axles of the work at right angles to the base-standards. 95

In order to place the work—as, for example, a pair of car-wheels—in position upon the base-standards preparatory to the grinding operation, two movable rails, 20^a, are provided at the front of the machine, up which the 100 wheels are rolled until their axle comes to rest upon the iron-shod wooden blocks 21 on the extensions 2 of the base-standards. The bearing-blocks sustaining the bearings are now in the position shown in Fig. V of the drawings, 105 and from the wooden blocks 21 the axle is rolled upon the bottom bearing-blocks elevated to receive it. The bottom bearing-blocks are next lowered by their jacks on spindles until the center-holes of the ends of the 110 axle are opposite the conical points of the steel center-pins 19, when, by turning the screw-nuts 17 backward toward the ends 15 of the 115 housings, the center-pins, by reason of their reversed threads, are caused to advance and enter the center-holes of the axle. By this means the axle is accurately centered. This done, the side bearing-blocks, 11, are moved up by their set-screws until the axle is securely held in the bearings, when the screw-nuts 17 120 are turned in reverse direction, thereby causing them to withdraw the pins from the center-holes and to force the annular friction-plates 18 against the ends of the axle. The car-wheels 125 will thus be securely held in position to be ground, and by turning the spindle *A*³ the wheels can be presented to the action of the grinding-wheels located upon one side of the machine.

The mechanism for imparting motion to the body to be ground is illustrated in Figs. I, VI, VII, and VIII of the drawings, where it is shown as applied to a machine for grinding car-wheels. It consists, essentially, of a train,

B, of friction rollers or pulleys, which is caused to operate upon the treads of the wheels by means of a lifting-jack, B'. Three friction-pulleys, 22, 23, and 24, are shown, although it is obvious that more or less may be employed. These pulleys, which are formed of alternate disks of rubber cloth and rubber firmly clamped by screws 25 between the metal plates 26, are sustained between the journal-arms 27. The upper pulley, 22, is keyed to the shaft B², which passes loosely through the enlarged upper ends of the arms 27, extends from side to side of the machine, and is supported by the journal-standards 28, which are bolted to the base-plate of the machine. This shaft B² is provided at one end with a worm-wheel, 29, which receives motion from a worm-gear on the counter-shaft 30, which is journaled in the standards 31, and is driven by the pulley 32. suitably connected by a belt to the overhead shaft. The pulley 23 is journaled in the oblong slots or bearings 33 of the arms 27, and similar slotted bearings, 34, are formed for the axle of the pulley 24. At the base of the slotted bearings 34 are held the movable journal-blocks 35, which are adjusted by means of the set-screws 36, and thus serve to keep the pulleys pressed firmly together. The lower ends of the arms 27 are connected to the yoke 37, attached to the top of the rod 38, which is held in a manner free to slide within a socket in the screw-headed standard 39, which is hinged by trunnion-bearings to the base 40 of the jack. Around the screw-threaded standard 39 fits the interiorly-threaded casing 41, the enlarged upper portion, 42, of which contains the rubber cushion 43, and is covered by the cap 44, which fits around the rod 38 below the yoke 37 and above the disk 45. The casing 41 is provided with the hand-wheel 46, for operating the same. When a pair of car-wheels has been placed in position to be ground, and motion is to be imparted thereto, the hand-wheel 46 is to be turned until the casing 41 is lifted sufficiently to force the pulley 24 against the perimeter of the wheels, and as this pulley receives motion through the train B from the shaft B² it will cause the wheels to revolve. The function of the rubber cushion 43 is to maintain a constant pressure of the friction-pulley upon the car-wheel, despite any slight irregularities of the latter and the reduction of the wheel in the grinding operation. The screw-jack is, for convenience, placed within a pit below the base of the machine, and although one jack and friction-train only are illustrated in the drawings, it is obvious that, if desired, for certain classes of work, more may be employed.

From the above-described construction it will be apparent that, whatever may be the diameter of the wheel or cylinder to be ground, the friction-roller 24 can be readily forced against the same by means of the lifting-jack, and by applying the motive power to the perimeters, instead of to the centers, as heretofore, of the bodies to be ground, a uniform rate

of surface-speed in a given time is imparted to bodies of different diameters without the labor and loss of time incident to the changing of gear-wheels of pulleys and the like in order to attain the maximum speed for abrasion.

A further and important advantage of this construction is that it secures a uniform, smooth motion, without vibrations or sudden jerks of the work, which occur when cog-gearing is employed, and which produce corrugations or irregularities upon the surface of the body in the grinding or polishing operation.

It will be understood that when the work is once set in the standards, and the friction driving mechanism is made to bear against the periphery thereof, said standards and driving mechanism remain stationary until the grinding is finished, save only for such slight adjustment of the driving mechanism to and from the work as may be necessary from time to time to insure proper frictional contact with the periphery thereof. In other words, since the standards and driving mechanism remain at fixed relation to each other, a perfectly uniform rotation is imparted to the work, so that at all stages of the grinding process the same number of lineal feet in any given period is subjected to the action of the abraders. The driving-power being applied to the periphery of the work, as described, necessarily rotates it at a regular unvarying speed.

The mechanism by which the four sets of grinding-wheels are sustained and operated rests upon four separate main standards, C, (two at the front and two at the back of the machine as indicated in Fig. I of the drawings.) As the operating mechanism of each set of grinding-wheels is, with the exceptions to be hereinafter noted, exactly the same, a description of the mechanism of one set will serve for all.

The base A of the machine, beneath the main standard C, is provided with the T-shaped slots or channels 50, within which rest the heads of the adjusting screw-bolts 51, which pass through the bottom flange, 52, of the main standard. On the base, intermediate the slots 50, is bolted the rack-bar 51^a, over which fits the chamber 52^a, formed in the main standard. In the front of the standard C are formed the lugs 53, in which is journaled the cog-wheel C', which meshes with the rack 51^a. Around the axle of this cog-wheel, and within the journal-lugs 53, fits the yoke 54 of the lever 55, and to this yoke is pivoted, as shown, a double-pointed dog or pawl, 56, which engages with the teeth of the cog-wheel. From this construction it will be seen that when it becomes necessary to move either of the main standards C toward the work to be ground the nuts of the adjusting-bolts 51 are loosened, and the dog or pawl 56 is thrown over upon the side of the lever 55 next the standard in reverse position from that shown in the drawings. Now, by operating the lever 55, the dog causes the cog to rotate, which, meshing in the fixed rack-bar, forces the standard to advance, and

when thus brought to the desired position it is secured there by means of the adjusting-bolts. To retract the main standard, the above operation is of course reversed. The top of the main standard C, which is cut away, as shown, is provided at each side with the ledges 57, the rails or shears 58, and the inclined guideways 59, and from end to end of this standard extends the main screw-threaded feeding shaft or spindle C, the smooth portion of the ends of which are journaled in suitable bearings, 60 and 61. The bearing 60 is countersunk, as shown, to permit the insertion of a wrench-bar over the squared end of the spindle, and to the bearing 61 is screwed an annular cap, 62, which fits around the reduced portion of the spindle and guards the same from longitudinal displacement. Upon the rails or shears 58 of the main standard C rests the main table D, which is furnished at each side of its bottom with the longitudinal guideways or grooves 63, adapted to move upon these rails 58, and the flanges 64, which embrace the ledges 57. The bottoms of the flanges 64 are formed, as shown, of separable strips 65, securely held in place by set-screws. The top of the main table D is provided with the inclined or dovetail guideways 66, which extend across the main table at right angles to the rails 58 of the main standard C. Upon these guideways 66 is sustained what I designate the "slide-rest carriage" E, which is preferably formed of separable parts securely bolted together. The lower portion, 67, of this carriage is provided upon each side with the dependent dovetail flanges 68 and 69, which embrace the guideways 66 of the main table, and between the flange 69 and the corresponding guideway is inserted the friction-strip 70, which is adjusted by means of set-screws, in order to compensate for wear of parts, and thus secure accurate movement of the slide-rest carriage. The upper portion, 71, of the slide-rest carriage is a hollow yoke-shaped casting, and within its two sides 72 and 73 is placed the lower slide-rest, F, which carries the grinding-wheel G. The bottom of the slide-rest F is formed with the dependent dovetail flanges 74, which fit over the dovetail guideways 75 on the top of the lower portion, 67, of the slide-rest carriage, and between one of the flanges 74 and its guideway is placed an adjustable friction-strip, 76. The upper portion of the slide-rest carriage is provided at its top with the dovetail guideways 77, over which fit the dependent flanges 78 of the upper slide-rest, F', which carries the grinding-wheel G'. This slide-rest F' is formed in two separable parts, 79 and 80, clamped together by means of the set-screws 81, which pass through the oblong slots 82 of the part 79, and into the projections 83 on the top of the part 80. To the under side of the part 79 is bolted the threaded lug 84, through which passes the adjusting-screw 85, which extends without the side of the portion 80, and is furnished with a suitable thumb-wheel for operating the same. The purpose of this con-

struction of the upper slide-rest is to allow a slight independent longitudinal movement to be given to the upper grinding-wheel, in order to bring the same into accurate alignment with its companion wheel below. This, as will be readily seen, can be effected by turning the thumb-wheel of the adjusting-screw 85 until the two grinding-wheels G and G' are accurately aligned, when the set-screws 81 will firmly clamp the two parts of the upper slide-rest together. The slide-rests F and F' are each provided with the bowed arms 86, the expanded ends 87 of which are bored out to constitute the journal-bearings for the mandrels 88 of the grinding-wheels G and G'. The mandrels 88 are secured in their bearings by jam-nuts 89 at their inner ends, and are each driven by a pulley, 90, which receives motion from a belt leading to the overhead shaft. For some classes of work—as, for example, calender-rolls having highly-polished surfaces—spring-seated bearings for the spindles 88 will be used to correct for any possible vibration, and to allow the grinding-wheels to run with perfect smoothness. This form of bearing is illustrated in the detail views XXI and XXII. The expanded ends 87 of the arms 86 are each bored out and provided with the seats T, in which rest the slide-plates t, bearing the rubber cushions t', the tension of which is regulated by means of the adjusting-screws t''. Between each set of rubber cushions t', and resting thereon, is the rubber cylinder t'', which fits over the journal-box t', through which passes the spindle 88. This journal-box t' has one end formed with the flange t⁵, to fit over an enlargement on the spindle 88, and with the flange t⁶ of greater diameter than the bore of the end 87 of the arm, and has its opposite end fitted with a flange or screw-ring, t⁷, of greater diameter than the bore of the cover-plate t⁸, which is bolted to the end 87 of the arm. A suitable lubricating device, consisting of the oil-reservoir T, the drip-cup T², and delivering and discharge tubes, is preferably used with this improved form of bearing. The spindles of the grinding-wheels are thus held in such manner as to be able to yield in a radial direction to compensate for possible vibration of the slide-rest, but are guarded securely against any longitudinal movement by the flanges of the journal-boxes.

It will be noticed from the foregoing description that the grinding-wheels of each set are brought into exact vertical alignment, and are symmetrically disposed with relation to the bearings of the work-holding standards, so that their points of contact with the work shall always be equidistant from the horizontal plane passing through the axis of the work as sustained in its bearings. This feature is of especial importance, since by such arrangement the abrading-wheels are caused to operate in unison—that is to say, they move together to and from the body upon which they are acting, whether this be a plain cylinder, or of conical or conoidal shape, or composite,

as in case of a car-wheel tread. If this symmetry in arrangement of the grinding-wheels were not carefully observed, the machine could not be adapted to the great variety of work as specified, because in adjusting one of the wheels to the surface to be reduced, the other moving in unison therewith would not take the same adjustment with respect to such surface unless said wheel were in exactly like relation to said surface and its axis. Inasmuch as the adjustment of the wheels to and from the surface to be abraded is effected automatically, as hereinafter described, the significance of this precision in arrangement of the wheels symmetrically becomes even more manifest, as, indeed, it is the only means by which an automatic adjustment to work of greatly varying contour can be certainly effected.

In order to bring the grinding-wheel in proper relative position for preliminary contact with the work, the slide-rests F and F' are provided, respectively, with the dependent threaded lugs f'f, which move in the cut-away spaces of the upper and lower portions of the slide-rest carriage E, through which pass the threaded spindles F² and F³. These spindles are journaled, as shown, in the top, front, and rear ledges of the upper and lower portions of the slide-rest carriage, and each is provided near its end with the friction-cone f², over which fits the conical bore of a worm-wheel, f³, as clearly shown in the detail view X^a. Connected to or formed integral with the worm-wheel is the threaded nut f⁴, having its outer surface in shape of a hand-wheel for convenience in operating the same. Meshing with the worm-wheels f³ is the vertical shaft F⁴, having wormed gears f⁵, the lower end of said shaft being journaled in the lower portion of the slide-rest carriage E, and its upper end being furnished with a suitable hand-wheel. The shaft F⁴ is braced about its middle by the journal-bracket f⁶, attached to the upper portion of the slide-rest carriage E, and upon this shaft is also keyed the spring-seated friction disk or plate M', the function of which will hereinafter appear.

In order to operate both of the spindles F² and F³ simultaneously and to the same extent by means of the shaft F⁴, the threaded nuts f⁴ are turned sufficiently to force the worm-wheels f³ into firm frictional contact with the cones f², when, by revolving the hand-wheel of the shaft, the spindles F² and F³ will move the slide-rests F and F' as desired. It will be noticed that by withdrawing either of the worm-wheels f³ from contact with its cone f² the corresponding spindle will be thrown out of gear, and can then be operated, if desired, by a key-crank passed over the squared end; or either spindle may be operated independently by the shaft F⁴ by throwing the friction-surfaces of the other out of gear. This feature is of especial importance in accurately positioning the grinding-wheels at the beginning of the operation.

The mechanism for operating the grinding-wheels is shown in the accompanying drawings as of a construction especially suited to the grinding of car-wheels. This, therefore, will first be described, and the slight modifications requisite to adapt the same to the grinding of other irregular and of plain cylindrical bodies will be subsequently indicated.

Within the cut-away space in the top of the main standard C, and upon the inclined guideways 59, rests the pattern-slide H, having upon its sides the inclined grooves 91, which fit over the guideways 59 and retain the pattern-slide securely in place thereon. To the bottom of this pattern-slide is attached by screw-bolts a threaded collar, 92, having preferably an interior sleeve of Babbitt metal, which fits over the main spindle C^a. The upper surface of the pattern-slide H is depressed, as shown, and within the space thus formed is held by set-screws the toothed pattern-cam H', the construction of which is best illustrated in the detail views XIII, XIV, and XV of the drawings. This cam consists of the base-plate 93, to which are screwed the cam-faced plates 94 and 95, the shape of which is determined by that of the body to be ground, being more or less curved, as may be the perimeter of such body. These cam-plates 94 and 95 are fixed at such distance apart as to form the cam-groove 96, and upon the top of the plate 94, and preferably formed integral therewith, is the cam rack-bar 97, which conforms to the shape of the cam-plate beneath it. Within the cam-groove 96 travels the plain end 98 of the shaft I, which is furnished with the pinion 98^a, meshing in the rack-bar 97, and with a flanged glide-sleeve 99, adapted to move in the oblong transverse slot 100, formed in the top of the main table D. Within the depressed portion of the top of the main table D, and around the shaft I, is held the collar 101, which is screwed to the under side of the slide-rest carriage E. The shaft I, as clearly shown in Fig. X, passes through the slide-rest carriage, and carries at its top the hand-wheel I', and about midway its length the worm-wheel 102, keyed thereto. From the above construction it will be seen that if motion is imparted to the shaft I, either by turning the hand-wheel I' in the direction of the arrow, Fig. X, or by the worm-wheel 102, the pinion 98 will be forced to traverse the rack-bar 97, the plain end of the shaft will travel in the cam-groove 96, the main table D and the mechanism sustained thereby will be moved longitudinally, and at the same time, since the shaft I is free to move in the slot 100 of the main table, the slide-rest carriage E will receive a motion at right angles to that of the main table D; hence it is apparent that the course followed by the grinding-wheels will describe a curve corresponding exactly with that of the cam-groove of the pattern-cam. In the drawings the pattern-cam is shown as of a shape or adapted for the grinding of car-wheels, and the grinding-wheels, during their

operation, will accordingly follow the contour of such wheels.

In order to impart a constant movement to the shaft I, and consequently to the grinding-wheels, from the source of power, a worm-shaft, K, is arranged to mesh with the worm-wheel 102. This worm-shaft passes through the slide-rest carriage E, the side 72 of which bears the journal-block 103 and the swinging journal-cover 104, each having double journal seats or bearings for the worm-shaft, and the side 73 of which is provided with a bracket, 105, having pivotally keyed therein the journal-bearing 106 of the worm-shaft K. The purpose in thus journaling the worm-shaft is to enable the same to be placed in or out of gear with the worm-wheels 102, as it is desired to move the shaft I from the source of power or by hand, and this can readily be done by shifting the shaft from one to the other of the bearings in the journal-block 103 and cover 104. Motion is imparted to the worm-shaft K by means of the speed-pulley 107, driven by the belt 108 from the speed-pulley 109, which, with its connected band-pulley 110, is sustained by the journal-brackets 111, attached to the main table D. The band-pulley 110 receives motion from the band-pulley 112 on the short shaft 113, which is sustained by the journal-stands 114, and is driven by the belt 115 from the main shaft B².

In order to keep a constant tension of the belt 108, connecting the speed-pulleys 107 and 109, there is attached to the side 73 of the slide-rest carriage E a pivot-pin, 120, upon which is sustained the bell-crank lever 121, carrying upon one arm the idler 122, which bears against the belt 108, and upon the other arm a weight, 123. This belt-tightener serves effectually to prevent the slackening of the belt 108 when the slide-rest carriage E is moved forward. In Figs. XXIII and XXIV is illustrated a modified form of pattern mechanism. In this construction the pattern-cam consists of a conoidal body, X, of a shape determined by that of the body to be ground, and provided with a continuous spiral groove around its perimeter. This cam-body X is keyed to the main feeding-shaft C², which in this instance is plain, and is guarded from longitudinal displacement by the yokes x, which depend from the pattern-slide H and fit around the shaft C². To the bottom of the slide-rest carriage E is screwed the bracket X', which passes through the oblong slot x' of the main table D, and between the arms of which is journaled the tracing-wheel X', which enters the spiral groove in the conoidal body X. Through the front of the main standard B, which is cut away for its admission, projects the guide cam-plate X³, sustained by the bracket x². By revolving the shaft C² the tracing-wheel is caused to move along the spiral groove of the conoidal body, and in so doing describes a course in accordance with the shape of such body, which is predetermined by the contour of the surface to be ground. The tracing-wheel im-

parts movement to the main table and slide-rest carriage, as does the shaft I, heretofore described. From the foregoing description it is apparent, as already stated, that by substituting pattern-cams of different shapes the grinding-wheels can be automatically moved in any desired direction with respect to the axis of the body to be ground. If, now, a plain cylinder of uniform diameter is to be ground, the necessary movement of the grinding-wheels along the same can be effected either by the use of a straight rack-bar upon the pattern-slide or by dispensing with the pattern-plate and the shafts I and K and moving the main table D by means of the main feed-spindle C², the main table and the pattern-slide being in such case suitably connected together by a coupling-pin, i, Fig. IX.

In Figs. XXVIII, XXIX, XXX, and XXXI of the drawings is shown the preferred manner of connecting the main table D with main spindle C², especially when long plain cylinders—such as shafting, calender-rolls, or the like—are to be ground or polished. It will be readily understood that in operating upon this class of work the main standard or beds C upon each side of the machine will be preferably formed in one, as indicated by dotted lines in Fig. I, so that the grinding-wheels can be given a much longer travel. It is also advantageous, especially in grinding long plain cylinders, to arrest the movement of the main table D automatically at any desired point. This is accomplished by the mechanism now to be described. Around the main spindle C² clasps a divided segmental screw-nut, the halves s of which are attached to the enlarged ends of the clutch-arms s', which are pivoted upon the bolts s³, passing through the plates S, the flanges s⁴ of which are bolted, as shown, to the under side of the main table D. The plates S are held securely together by the rods s⁵, and within these plates, and between the arms s', is placed the disk S', which is keyed to the spindle S², and is provided with the cam-slots s⁶, through which pass the pins s', attached to the arms s'. The spindle S², which is journaled in the plates S, has keyed upon its ends the levers S³, and from the foregoing construction it will be seen that by turning either of these levers a partial revolution will be imparted to the disk S', which will cause the pins s' to ride up in the cam-slots s⁶, and thus elevate the free ends of the arms s' and lift the segmental nut out of the gear of the main spindle, and arrest the movement of the main table. In order to elevate the clutch-arms s' automatically at any desired point, a threaded cam-nut, S⁴, is fixed at such point upon the main spindle. This nut is provided with the enlarged cam-face s⁸ and the reduced split back portion s⁹, having dependent ears, which may be drawn together by the clamp s¹⁰, in order to guard the cam-nut from displacement on the spindle. Now, when the main table D in its travel across the main standard or bed reaches the point at which its movement is to be arrested, the lever S³ rides

upon the face of the cam-nut, and thus automatically disconnects the segmental nut from the main spindle and brings the main table to rest. In grinding plain cylinders the main table D and slide-rest carriage are to be connected together by means of the coupling-pin 140, which will prevent the transverse movement of the slide-rest carriage.

The mechanism for automatically compensating for the wearing away of the grinding-wheels and keeping the same fed constantly up to the work is illustrated in detail in Figs. XVI, XVII, XVII^a, XVIII, and XVIII^a of the drawings.

15 To the under side of the top of the slide-rest carriage E are attached two journal-brackets, 150, which sustain the flanged tubular shaft M, carrying upon its front end the friction-wheel 151. This friction-wheel is held upon its shaft 20 by a set-screw in such manner that its position thereon can be varied at pleasure, and it bears upon the top of the friction-disk M', which is pressed upward by the spiral spring 152, and is keyed to the shaft F'.

25 Within the tubular shaft M, and in a manner free to slide therein, rests a portion of the shaft M², provided with the groove 153, adapted to receive a corresponding key of the tubular shaft, so that the shaft M² will communicate 30 its movement to the shaft M irrespective of its position therein. The shaft M² projects into and is journaled in the extension 154 of the tubular casing M³, and carries upon its 35 end the worm-wheel 155, which moves within the enlargement 156 of the casing. The casing M³ has a bore of varying diameter, within which is sustained the shaft 157 of what I designate the "compensating-roller" M'. The shaft 40 157 is guarded against longitudinal movement by reason of its enlarged part bearing against the contracted bore of the casing, and by the screw-cap 158 of the casing, within which the conical end of the shaft revolves, and on this shaft is formed the worm-gear, which meshes 45 with the worm-wheel 155.

Upon the frontside of the casing M³ is formed the hollow extension or spring-box 159, the chamber of which exceeds the bore of the casing, to the center of which it extends. Within 50 the chamber of this extension rests the journal-block 160, which constitutes half the bearing for the journal of the shaft 157, and back of this journal-block, and bearing against the same, is the spiral spring 161, the tension of 55 which can be adjusted by means of the screw-cap 162, to bring the compensating-roll M' more nicely in position near to the surface being ground, and to allow it to yield lightly against any abrupt irregularity thereon, which 60 might otherwise tend to break or to seriously disarrange the delicately-constructed parts. The casing M³ is braced at one end by the dependent bracket 163, which carries the slide-rod 164, sustained by the standard 165, bolted 65 to one of the dust-collecting hoods, to be hereinafter described, and is braced centrally by the bent T-shaped slide-bracket 166. The

head of this bracket 166 is bolted, as shown, to the casing M³, and its end moves between guide-strips upon the side 72 of the slide-rest 70 carriage, and is slotted to receive the adjusting-screw 167, which clamps the end, and thus retains the casing M³ and compensating-roller M' in any desired position.

The operation of the compensating mechanism is as follows: 75 When, at the outset, the grinding-wheels have been adjusted into proper contact with the body to be ground, and revolution has been imparted to the body, as heretofore described, the compensating-roller M', which is midway 80 the grinding-wheels G and G', is brought to bear lightly upon the revolving body just below the upper grinding-wheel in the path cut thereby, and is there retained by clamping the adjusting-screw 167.

The contact between the 85 revolving body and the compensating-wheel at this time is not quite sufficient to cause the latter to move. If, now, however, the grinding-wheel becomes worn away to such an extent that it fails to cut—say, for example, the 90 wear is one one-hundredth of an inch—the diameter of the body being ground is at its point of contact with the compensating-roller proportionately larger, and the pressure between the two becomes so great as to cause the compensating-roller to revolve. The revolution of this roller imparts motion to the worm-wheel 155, the shafts M² and M, the friction-wheel 151, the friction-disk M', the shaft F', and the spindles F² and F³, and thus causes 100 the slide-rests and their grinding-wheels to advance until the latter again cut into the revolving body and reduce its diameter sufficiently to prevent its moving the compensating-roller. This operation is repeated as often 105 as the grinding-wheels become appreciably worn. As the motion of the compensating-roller is communicated to the slide-rests by means of the worm-gears and friction-wheels, the speed of the motion is greatly diminished, and the sensitiveness of the roller is correspondingly increased. The speed transmitted can be varied at pleasure by so adjusting 110 the friction-wheel 151 upon its shaft as to cause it to travel on the friction-disk M' at 115 different distances from the center.

The hoods to which the dust-exhausting apparatus is connected consist each of a cast-iron casing, P, which fits around the grinding-wheel, and is sustained by means of the standard p, affixed to the outer arm of the slide-rest. The cover p' of the casing is removable to allow the insertion of the grinding-wheel, and is held in place by screws. In the under side or bottom of the casing P is placed an adjustable dust-hopper, P', carrying the set-screw p², which passes through the slot p³ of the cover, and by means of the set-screw the mouth of the hopper is fixed in close proximity to the body being ground, and thus readily collects 120 the sparks and dust. In the top of the casing P, as shown in Fig. XI, is placed the hinged valve p⁴, which fits snugly the walls of the casing, and is operated by the thumb-screw p⁵.

The purpose of this valve is to compel the entire exhaust to be drawn from the bottom of the casing, where the dust is deposited, and to this end the position of the valve is changed 5 as the grinding-wheel wears away. The upper and lower casings, P, are connected together by means of the exhaust-pipe P^6 , which extends from the angular bottom of one casing to that of the other. This pipe is connected 10 to the casing by suitable pivoted joints, and has at its middle a telescopic joint, in order to allow the independent movement of the slide- rests. To the inner side of the lower casing, P, is attached the flexible exhaust-pipe P^2 , which 15 connects with the pipe P^3 , leading to an exhaust- fan or blower. By this construction of hood and exhaust mechanism the particles of dust and metal are readily collected and withdrawn. A further advantage of the hoods is, that they 20 serve to prevent accidents from the breakage of wheels which are defective or have been carelessly fixed to their shafts.

In Figs. XXV, XXVI, and XXVII is shown 25 in detail a modified form of exhaust-pipe connection especially adapted for use where the grinding-wheels travel from end to end of a long carriage-bed or main standard. To the base A of the machine, about midway of the long table indicated by dotted lines in Fig. I of the 30 drawings, is fixed the standard 171, to which is connected or formed integral therewith the elbow-pipe 172. To one of the branches, 173, of this elbow is attached by a cone-joint, 174, the discharge-pipe 175, leading out from the 35 machine, and to the other branch, 176, is attached the pipe-section 177, having arms or branches 178, to which are connected the flexible pipe 179, leading each to a set of wheels. The pipe-section 177 is provided with the conical end 180, which enters the conical bored end 40 of the branch 176, and with flange 181, which fits over the flange 182, and is held thereon by means of the ring 183, screwed to the flange 181. Between the flanges 181 and 182 is placed 45 the rubber ring 184, which retains the parts in proper bearing contact. In the end of the elbow-pipe 172 is placed an injector, 185, of suitable construction, having a cone-valve, 186, to control the action of the same. The 50 pipe-section 177 is thus free to turn, so that the injury of the flexible tubes by kinking as the grinding-wheels travel from side to side of the machine is avoided.

The improved construction of grinding- 55 wheels and the mandrel for sustaining the same are illustrated in the detail views XIX and XX of the drawings. Centrally of the inner side of the solid emery-wheel G, and fixed thereto in the process of molding the wheel, 60 is the depressed flange-plate g, the sides of which may be slightly inclined. In this wheel are also molded the metal tubes g', preferably three or four in number, arranged circumferentially with reference to the axis of the wheel, 65 the bores of which tubes lie below the plate g, having circumferential perforations g² to correspond therewith. The expanded end g³

of the mandrel 88 is provided with circumferential threaded perforations corresponding in number with the tubes of the emery-wheel 70 G, and its periphery is adapted to fit snugly within and against the flanged plate g. In order to attach the grinding-wheel to its mandrel, the plate g is placed over the end g³, and through the metal tubes g' are passed the bolts 75 g⁴, having threaded ends to receive the clamp-nuts g⁵. Upon the outside of the wheel G is placed the washer g⁶, and it will be seen that by turning the clamping-nuts g⁵ the wheel is firmly and accurately secured to the 80 expanded end of its mandrel.

Grinding-wheels of emery or corundum, as ordinarily made, are furnished with a central hole, in which fits the reduced end of a mandrel, upon which the wheel is retained by 85 means of washers forced directly against the body of the wheel. By making the wheel solid, as hereinbefore stated—that is to say, without any large central perforation—it is rendered firmer, more rigid and tenacious, 90 and may be revolved at higher rates of speed than could be safely risked in the older forms having the large central hole therein.

A great difficulty experienced in attaching 95 to a mandrel a wheel of the old construction arises from the liability to crush the texture of the wheel by forcing the washers too tightly thereon. On the other hand, if the washers be not clamped sufficiently tight, the centrifugal force exerted upon the wheel will be sustained at its center by the mandrel, instead of being borne by the washers from points nearer the periphery, and it will readily be seen that under such conditions the tendency of the wheel to burst when revolving at a high rate of speed 100 is much increased. Effort has been made to avoid this by making the washers very broad, and thus increasing their bearing-surface; but this has the disadvantage of diminishing the effective size of the wheel. By my improved 110 construction of wheel its most accurate centering and secure attachment are obtained, and at the same time its grinding capacity is in effect increased by the reduction of the size of the washer. The washers, which bear firmly 115 against the ends of the metallic tubes, can be forced to the extreme without danger of crushing the texture of the wheel, and the clamping-bolts and flanged plate also aid in sustaining the wheel securely in exact position. 120

Having thus described my invention, what I claim as new, and desire to secure by Letters Patent, is—

1. The combination, with the work-holding standards, of the laterally-adjustable housings 125 having adjustable bearing-blocks sustained therein, substantially as described.

2. The combination, with the work-holding standards and with the laterally-adjustable housings having adjustable bearing-blocks 130 sustained therein, of the main standards carrying the grinding mechanism, said main standards being adjustable to and from the work-holding standards, substantially as described.

3. The combination, with the work-holding standards, of the housings having the adjustable side bearing-blocks and the adjustable bottom bearing-blocks separate therefrom, substantially as described. 5
4. The combination, with the work-holding standards, of adjustable bearing-blocks and mechanism, substantially as described, for centering the work, substantially as set forth. 10
5. The combination, with the work-holding standards and the housings, of the screw-stud 16, the center-pin 19, and the screw-nut 17, substantially as described. 15
6. The combination, with the housings of the work-holding standards, of the side bearing-blocks and the bottom bearing-blocks having screw-jacks to lift them to the top of the housings, substantially as described. 20
7. The combination, with the housings of the work-holding standards and with the bearing-blocks, of the screw-stud 16, the screw-nut 17, and the plate 18, substantially as described. 25
8. The combination, with the stationary work-holding standards, of driving mechanism, substantially as described, adapted to bear upon the periphery of the work being ground and impart uniform revolution thereto, substantially as described. 30
9. The combination, with the stationary work-holding standards, of adjustable friction driving mechanism adapted to bear upon the periphery of the work being ground and to impart uniform revolution thereto, substantially as described. 35
10. The combination, with the work-holding standards, of the friction-pulleys, the driving-shaft B², and the lifting-jack B', substantially as described. 40
11. The combination, with the friction-pulleys, of a lifting-jack, B', and elastic cushion 43, substantially as described. 45
12. The combination, with the work-holding standards having extensions upon which the axle of the work may run, of the housings and the vertically-adjustable bottom bearing-blocks to receive said axle, substantially as described. 50
13. The combination, with the work-holding standards and with a single main standard, of two grinding or cutting wheels adapted to move in unison, said wheels being arranged at equal distances from the horizontal plane passing through the axis of the work as sustained in its standards, substantially as described. 55
14. The combination, with a main table capable of lateral movement, of two independent tool slide-rests mounted thereon, one above the other, substantially as described. 60
15. The combination, with the main standard, of the main table D, the slide-rest carriage E, and the upper and lower slide-rests carrying grinding-wheels, substantially as described. 65
16. The combination, with the main standards, of the main table, the slide-rest carriage E, and two grinding-wheels, G and G', sus- tained by said carriage, substantially as de- 70
17. The combination, with the two grinding-wheels and their slide-rests, of mechanism, substantially as described, for adjusting said wheels with relation to each other in the plane of their axes, whereby a vertical alignment of said wheels is secured, substantially as set forth. 75
18. The combination, with the slide-rest carriage, of the independent slide-rests F F', mounted therein, one of said slide-rests being provided with the separable parts 79 and 80, which may be relatively adjusted to bring the slide-rests into accurate vertical alignment, substantially as described. 80
19. The combination, with the main stand- 85
- ard, the main table, and the slide-rest carriage sustaining independent slide-rests adapted to move in unison, of a pattern-surface and means for connecting the same with said main table, substantially as described.
20. The combination, with the main stand- 90
- ard, of a pattern-surface having a rack-bar, the main table sustaining the grinding-wheels, and a shaft provided with a pinion, whereby the movement of the main table is effected, substantially as described. 95
21. The combination, with the main stand- 100
- ard having guideways, of the pattern-slide having flanges to fit said guideways, substantially as described.
22. The combination, with the main stand- 105
- ard and with the pattern-surface sustained therein, of the slotted main table, the slide-rest carriage having independent slide-rests, and means, substantially as described, for connecting the slide-rest carriage with the pattern-surface, substantially as described.
23. The combination, with the main standard and with the pattern-surface sustained thereby, of the slotted main table, the slide-rest carriage having independent slide-rests, and a shaft connected to said carriage, passing through the main table and adapted to bear upon the pattern-surface, substantially as de- 110
- scribed. 115
24. The combination, with the main stand- 120
- ard C, of the pattern-slide H, having a rack-bar, 97, thereon, the slotted main table D, the slide-rest carriage E, the shaft bearing a pinion and connected with the slide-rest carriage, substantially as set forth. 125
25. The combination, with the slide-rest car- 130
- riage, of the upper and lower slide-rests, carrying grinding-wheels, and mechanism, sub- stantially as described, for adjusting said wheels relatively to each other in the plane of rotation of the grinding-wheels, substantially as described.
26. The combination, with the main stand- 135
- ard C, of the main table D, the slide-rest carriage E, the shaft I, having the pinion 98^a and worm-wheel 102, the shaft K, and the pattern-slide carrying the rack-bar 97, substantially as described.
27. The combination, with the main table D,

- the slide-rest carriage, and the pattern-surface, of the shafts I and K, the pulleys 107 and 109, the belt 108, and the belt-tightening mechanism, substantially as described.
5. 28. The combination, with the main table D, the slide-rest carriage E, and the pattern-surface carrying a rack-bar, of the shaft I, carrying a pinion and worm-wheel 102, the shaft K, and means, substantially as described, for connecting or disconnecting said shaft K and worm-wheel 102, substantially as set forth. 60
10. 29. The combination, with the slide-rest carriage E and the slide-rests, of the spindles F² F³, for moving said slide-rests, and a shaft for operating said spindles, substantially as described. 65
15. 30. The combination, with the slide-rest carriage and the slide-rests, of the spindles for moving said slide-rests, a shaft for connecting said spindles, and mechanism, substantially as described, for throwing the spindles and shaft out of gear, substantially as described. 70
20. 31. In a grinding-machine, the combination, with the grinding-wheels, of mechanism, substantially as described, for automatically advancing said grinding-wheels as they become worn away, substantially as set forth. 75
25. 32. The combination, with the slide-rest carriage, one or more slide-rests, and their spindles, of a compensating-roller adapted to bear against the body being ground, and mechanism for connecting said compensating-roller with the spindles of the slide-rests, substantially as set forth. 80
30. 33. The combination, with the compensating-roller and intermediate mechanism, of the tubular shaft M, the adjustable friction-pulley 151, the friction-disk M', the shaft F⁴, spindles F² F³, and the slide-rests F F', substantially as described. 85
35. 34. The combination, with the compensating-roller, of means, substantially as described, for adjusting the same toward and from the work being ground, substantially as described. 90
40. 35. The combination, with the compensating-roller and its shaft, of the spring-seated journal-bearing, substantially as described. 95
45. 36. The combination, with the grinding-wheel, of an inclosing-hood provided with an adjustable hopper, substantially as described. 100
50. 37. The combination, with the grinding-wheel, of the inclosing-hood having an adjustable valve at its top, and an exhaust-pipe connected to said hood, substantially as described. 105
55. 38. The combination, with two grinding-wheels, of the inclosing-hoods, a telescopic connecting-pipe, and an exhaust-pipe, substantially as described. 110
39. The combination, with the mandrel hav-
- ing a broad end plate perforated near and about its circumference, of a solid grinding-wheel having circumferential perforations corresponding with those of the end plate, and the clamping-bolts to secure said wheel to the plate, substantially as described. 60
40. The combination, with the mandrel having a broad end plate perforated near and about its circumference, of a solid grinding-wheel having a depressed seat to receive said plate, and circumferential perforations corresponding with those therein, said wheel being secured to the plate by clamping-bolts, substantially as described. 65
41. The combination, with the mandrel 88, having the expanded end g³, of the grinding-wheel G, having the tubes g', and the clamping-bolts g", substantially as described. 70
42. The combination of the mandrel 88, having expanded end g³, with the grinding-wheel G, having the flanged plate g embedded therein, and the clamping-bolts g", substantially as described. 75
43. A solid grinding-wheel having a series of circumferential perforations only therein, substantially as described. 80
44. A solid grinding-wheel having a depressed seat to receive the broad end plate of the mandrel, substantially as described. 85
45. A solid grinding-wheel having a depressed seat and a series of circumferential perforations therein, substantially as described. 90
46. A solid grinding-wheel having a series of metal tubes arranged in circumferential series, and a flanged perforated metal plate forming a depressed seat, to snugly receive the end plate of the mandrel, substantially as described. 95
47. The combination, with the mandrel of the grinding-wheel and its journal-box, of the elastic slide-plates, which allow said box and mandrel to yield against all radial strains, substantially as set forth. 100
48. The combination, with the mandrel of the grinding-wheel and with its journal-box, of the adjustable elastic slide-plates, which allow said box and mandrel to yield against radial strains, substantially as described. 105
49. The combination, with the mandrel of the grinding-wheel and with its journal-box, of the yielding cylinder and the elastic slide-plates, substantially as described. 110
- In testimony whereof I have hereunto set my hand this 6th day of December, A. D. 1882.
